UNITED STATES PATENT OFFICE.

ADOLPH PETER GUSTAFSON, OF CHICAGO, ILLINOIS, ASSIGNOR TO M. SCHULZ CO., OF CHICAGO, ILLINOIS.

LOST-MOTION DEVICE FOR PLAYER-PIANO ACTIONS.

1,169,480.

Specification of Letters Patent.

Patented Jan. 25, 1916.

Application filed May 19, 1913. Serial No. 768,492.

To all whom it may concern:

Be it known that I, ADOLPH PETER GUSTAFSON, a citizen of the United States, residing at Chicago, in the county of Cook 5 and State of Illinois, have invented a certain new and useful Improvement in Lost-Motion Devices for Player-Piano Actions, of which the following is a full, clear, concise, and exact description, reference being had to the 10 accompanying drawings, forming a part of this specification.

My invention relates to player-piano actions and like apparatus.

Prominent objects of the invention are to 15 provide a simple, practical and inexpensive arrangement for preventing lost motion on the part of such actions; to permit the adaptation of such mechanism to various kinds and forms of actions; to permit adjustment 20 to each type of action; to obtain compactness, simplicity and smallness in size; and to secure the foregoing and other desirable ends in a simple and expeditious manner.

In the accompanying drawings, Figure 1 25 is an end elevation of a player piano action embodying my present invention; Fig. 2 is a front view of the same; Fig. 3 is a view of a piano action containing a lost motion device embodying my invention as applied.

30 In the drawings I have shown an action chest 1 which may be of any suitable construction and contain valves, pouches, and suitable ports comprising mechanism to be actuated by air coming through a tracker tube 2. As the interior of this chest forms 35 no part of my invention the arrangement thereof is not shown in the drawing. Below the chest 1 is a pneumatic 3 which is understood to represent one of a series of pneumatics secured for convenience to the under 40 side of the chest 1, the upper fixed leaf 4 of said pneumatic being desirably secured firmly to the lower surface of the action chest. The loose or swinging leaf 5 is shown 45 provided with a projecting member 6 attached to the free or swinging end of said leaf and this projection 6 is understood to engage an engaging surface 7 formed by a block 8 on the sticker of the piano action so

50 as to operate the same, as shown in Fig. 3, it being understood, of course that this is merely illustrative of one method in which the pneumatic can be applied for service. At the other end of the swinging leaf 5 is another projecting member 10 which extends

or projects beyond the hinged end of the pneumatic, as shown in Fig. 1. An abutment conveniently in the form of a button 11 engages the end of said member 10 so as to limit the downward swinging movement of 60 the swinging leaf 5 of said pneumatic. As a convenient arrangement the button 11 is carried by a threaded pin 12 which is passed through a projecting member or stud 13 inserted and secured to the action chest 1. 65 Thus the screw 12 may be turned so as to adjust the button 11 up or down and thereby change the point at which said button will be engaged by the end of the clip 10. In this way the limit of the downward movement of the swinging leaf 5 may be changed or shifted as desired, and this of course permits an accurate adjustment of the swinging leaf of the pneumatic to the particular device or element to which the pneumatic is 70 applied for service. It also permits the arrangement to be applied to various kinds of actions permitting adjustment of the swinging leaf as required. It will be seen that this accurate adjustment of the pneumatic to the element with which it co-operates permits the parts to work closely together and so eliminates lost motion. It will also be seen that each individual pneumatic can be 75 readily and easily and quickly adjusted simply by turning the screw 12 with the fingers or with some tool adapted to engage the eye at the upper end of the same. This can be conveniently done from the accessible side 80 of the action, or what may be termed the front of the action, the player action being placed in front of the piano action. Thus the adjustment to the stickers is made without inconvenience and without having to get to the back of the action, or in other words 85 to the point where the adjustment is to be made, thereby greatly simplifying and expediting the matter of adjustment of pneumatic action to piano action.

90 It will be understood, of course, that 100 changes and modifications can be made without departing from the spirit of the invention.

What I claim is:

1. The combination of a pneumatic having its hinged end provided with a projection and a stationary abutment co-operating with said projection and engaging the same when the pneumatic is expanded. 105

2. The combination of a pneumatic hav- 110

ing a movable member, a striking mechanism, said movable member engaging said striking mechanism, a stationary abutment, said movable member having a portion 5 which engages the stationary abutment, and said portion normally resting against said abutment.

3. The combination with a pneumatic having a swinging leaf, of a projection at the 10 hinged end of said swinging leaf, a screw having its end provided with a device positioned to engage said projection, and a fixed support for fixedly holding said screw so as to cause the same to serve as an abutment 15 for said projection.

4. The combination of a support, a pneumatic secured thereto, a projection on the swinging leaf of said pneumatic at the 20 hinged end thereof, a pin secured to and projecting from said support, and a screw passing through said pin and having its end in engagement with said projection on the pneumatic swinging leaf.

5. The combination of an action chest, a 25 pneumatic secured to the under side thereof with the swinging leaf of said pneumatic underneath, a projection at the hinged end of said pneumatic, an abutment carried by said action chest and positioned to engage 30 the projection on said swinging leaf, and a piano action sticker provided with a projecting member adapted for engagement with the free end of said swinging leaf.

6. The combination with an action chest, 35 of a pneumatic secured to the under side of the same with its swinging leaf underneath, projecting members at the opposite ends of said swinging leaf, a pin secured to said action chest and provided with a screw 40 extending downwardly and having its lower end in engagement with the projecting member at the hinged end of the pneumatic, and a piano sticker provided with a block whose lower end is in engagement with the 45 projecting member at the free end of the pneumatic.

7. The combination of a player action having pneumatics with their hinged ends

at the front of the action and their swinging ends at the rear thereof, and means at 50 the hinged ends of said pneumatics for adjusting the swinging leaves thereof.

8. The combination of a player action having swinging leaf pneumatics located with their hinged ends in front, a piano 55 action in the rear of said player action co-operating with said pneumatics, and means adjacent to the hinged ends of said pneumatics, an abutment and projections extending beyond the front end of said pneumatics 60 and threaded screws positioned to control said abutments.

9. The combination of a pneumatic, a striking mechanism engaged by the pneumatic, a projection, and adjustable stop provided at one end of the pneumatic, and means whereby the end of the pneumatic adjacent said striking mechanism is moved relative to the striking mechanism by the 65 adjustable stop.

10. The combination of a pneumatic having a swinging element, a member actuated by said swinging element, and adjustable means for moving said element with relation 70 to said member.

11. The combination of a pneumatic having a movable member, one end of which engages a striking mechanism, a stationary abutment provided at the end of said pneumatic remote from the striking mechanism, 80 the end of the movable member adjacent the abutment having a portion which co-operates with said abutment, said portion resting against said abutment when said pneumatic is expanded.

12. The combination of a pneumatic having its hinged end provided with a projection and an adjustable abutment co-operating with said projection and engaging the same when said pneumatic is expanded.

In witness thereof, I hereunto subscribe my name this 28th day of April, A. D. 1913.

ADOLPH PETER GUSTAFSON.
